CLAIM

The ornamental designs for a control unit for needleless injector, as shown and described.

DESCRIPTION

No(s) 1: Control unit for needleless injector

Figure 1.1 is a front view of a control unit for needleless injector;

Figure 1.2 is a back view thereof;

Figure 1.3 is a top view thereof;

Figure 1.4 is a bottom view thereof;

Figure 1.5 is a left view thereof; and

Figure 1.6 is a right view thereof.

The broken lines shown in Figures 1.1-1.2 and Figures 1.4-1.6 illustrate portions of the control unit for needleless injector that form no part of the claimed design.
